(57) CLAIM

The ornamental design for a towable diving plane, as shown.

DESCRIPTION

FIG. 1 is a perspective view of a towable diving plane showing my new design.

FIG. 2 is a top plan view of the towable diving plane shown in FIG. 1;

FIG. 3 is a bottom plan view of the towable diving plane shown in FIG. 1;

FIG. 4 is a front elevational view of the towable diving plane shown in FIG. 1;

FIG. 5 is a rear elevational view of the towable diving plane shown in FIG. 1;

FIG. 6 is a left side elevational view of the towable diving plane shown in FIG. 1;

FIG. 7 is a right side elevational view of the towable diving plane shown in FIG. 1.
